(57) **CLAIM**

The ornamental design for a ceiling fan housing, as shown and described.

DESCRIPTION

FIG. 1 is a perspective view from below of the ceiling fan housing in accordance with my design.

FIG. 2 is a bottom plan view of the ceiling fan housing on a reduced scale in accordance with my design;

FIG. 3 is a front elevation view of the ceiling fan housing on a reduced scale in accordance with my design;

FIG. 4 is a top plan view of the ceiling fan housing on a reduced scale in accordance with my design; and,

FIG. 5 is a side elevation view of the ceiling fan housing on a reduced scale in accordance with my design.

The broken line showing of environmental structure in FIGS. 1–5 is for illustrative purposes only and forms no part of the claimed design.

The left and right side elevation views are identical except for the position of the fan blades.
